UNITED STATES PATENT OFFICE.

DELBERT F. AXELSON, OF LOS ANGELES, CALIFORNIA, ASSIGNOR TO AXELSON
MACHINE CO., A CORPORATION OF CALIFORNIA.

SUCKER-ROD ROTOR.

Application filed October 31, 1922. Serial No. 598,230.

My invention relates to pumps and particularly to oil well pumping equipment. A pump now extensively employed for the purpose of pumping oil from wells consists of a steel barrel which is placed at or near the bottom of the well at the end of a line of tubing, and in which steel barrel an accurately ground cylindrical steel plunger, having valves therein, is reciprocated. It is quite common for the barrel of such pumps to wear slightly out of round, thus causing an elongated cross section of the plunger and barrel to result, instead of preserving a true circular cross section such as results from an equal distribution of the wear over the surfaces of the barrel and plunger. The confinement of the wear between reciprocating parts to any one area soon causes a space to occur between the plunger and the barrel, with the result of leakage of the oil past the plunger and an inefficient operation of the pumping equipment.

It is an object of my invention to provide a device for slightly rotating the reciprocating members of a pump at each reciprocation thereof, so that the wear of the parts will not be confined to any particular area, but will be distributed over the entire surfaces thereof.

It is a further object of the invention to provide a device of this character which may be employed with the standard form of pumping equipment.

The especial advantages of the invention and further objects thereof will be made evident hereafter.

Referring to the drawings which are for illustrative purposes only,

Fig. 1 is a fragmentary view showing a packing head, having a polished rod of an oil pump extending therethrough upon which is mounted a rotating device, embodying the features of my invention.

Fig. 2 is an enlarged fragmentary sectional view, of the reciprocating device shown in Fig. 1, taken from substantially the same position as Fig. 1.

Fig. 3 is a section taken upon a plane represented by the line 3-3 of Fig. 2.

Fig. 4 is a side elevation, partly in section, of the mechanism shown in Fig. 1, as attached to a walking beam, and in operative

relation to standard delivery piping which encloses a pump at, or near, the bottom of a well.

In oil well pumping equipment it is customary to install a packing head 11 upon the upper end of a string of tubing 12, which includes a T 12^a connecting with an oil delivery pipe 12^b passing through a casing head 12^c, and is connected by means of a union 12^d to a pump barrel 13, as shown in Fig. 4. The packing head 11, shown in Fig. 1, is provided with a gland nut 14 by which the packing contained therein may be compressed to provide the desired seal around the reciprocating polished rod 15, which operates through the packing head and is connected with a plunger 15^a which works in the pump barrel 13. The packing head 11 is provided with diametrically outstanding arms 16, these arms having a utility which will be made evident hereinafter.

Upon the polished rod 15, a head 18 is clamped by means of clamp plugs 19, provided with nuts 20. Upon the lower end of the head 18 ratchet teeth 21 are formed which are adapted to be engaged by spring retained pawls 22 which operate in projections 23 formed diametrically on a ring 24 which fits over the ratchet teeth 21. Below the head 18 and separated therefrom by a washer 26 is disposed a yoke 28 provided with a hole 29 through which the polished rod 15 extends. The standard lifting reins 30, which are employed with regular pumping equipment, are pivotally connected in the usual manner to the walking beam 30^a of an oil well rig and the pins 31 formed upon the yoke 28. As the walking beam 30^a of the pumping equipment is reciprocated, the polished rod and the reciprocating elements attached thereto are vertically reciprocated owing to the fact that the head 18 rests upon the yoke 28.

Surrounding the lower part of the head 18, is placed a sleeve 35 having vertical slots 36 therein which slide over the extending arms 37 of the yoke 28, and further having a pair of oppositely disposed helical slots 39, through which the projections 23 of the ring 24, extend. A collar 40 is held upon each of the projections 23 by a cap nut 41 which also compresses springs 42 against

the pawls 22. The collars 40 are of a diameter substantially equal to the width of the slots 39, and receive the wear due to sliding against the walls of the slots 39.

5 Upon the lower end of the sleeve 35, brackets 45 are bolted from which connecting rods 46 extend downwardly through holes provided in the arms 16 of the packing head 11. The rods 46 have the utility 10 of causing the sleeve 35 to slide relatively up and down upon the head 18 as the polished rod is reciprocated, and stop nuts 49 and 50 are provided for limiting the movement of the arms 46 through the arm 16, a 15 spring 51 being provided between each of the nuts 50 and the arms 16.

In Fig. 1 the polished rod and the head 18 are shown in their lowest position. In such position the springs 51 are compressed 20 between the nuts 50 and the arms 16, and the sleeve 35 is forced upwardly into its highest position relative to the head 18. In this relative position between the sleeve 35 and the head 18 the projections 23 are in the 25 bottom of the slot 39. As the head 18 is lifted upwardly, the sleeve 35 travels therewith, in substantially the same relative position as shown in Fig. 1, until the nuts 49 come into engagement with the underside of 30 the extending arms 16, thus stopping the movement of the sleeve 35, whereupon the head 18 continues to travel upwardly therethrough. The nuts 49 are placed upon the 35 lower ends of the connecting rods 46 in such position that they will not engage the arms 16 until the head 18 has nearly reached the full extent of its upward stroke, so that when the upward stroke is completed the 40 projections 23 will occupy intermediate positions in the slots 39, as indicated by the dotted lines 55.

It will be perceived that as the head 18 moves upwardly within the sleeve and the 45 projections 23 are carried upwardly within the slots 39 that the ring member 24 will be rotated in the direction indicated by the arrow 56, and, due to the engagement of the pawls 22 with the last tooth 21, the head 18 and the polished rod will be rotated through 50 a small angular distance. As the head travels downwardly, the sleeve follows therewith until the springs 51 strike and are compressed against the arm 16 whereupon the sleeve 35 is raised relative to the head 18 and the projections 23 are brought back to the bottoms of the slots 39 and in being so returned are rotated back to the position 55 shown in Fig. 1, the pawls 22 riding over the ratchet teeth 21. The slight rotation of the polished rods at each reciprocation is transferred through the string of sucker rods to the plunger of the pump which is likewise slightly rotated, thus distributing the wear between itself and the barrel in which it reciprocates. The amount which it is de-

sired to rotate the reciprocating elements at each stroke may be adjusted by positioning the nuts 49 upon the rods 46 to give the desired travel of the projections 23 in the slots 39. By the use of this adjustment a rotation 70 to suit the needs of the pumping equipment may be attained.

It will thus be seen that I provide means for effecting both a relative axial movement and a relative rotational movement between 75 the pump barrel, or cylinder, 13 and the plunger 15.

I claim as my invention:

1. In a device of the class described, the combination of: a polished rod; a head upon 80 said polished rod; a yoke upon said polished rod adapted to lift said head; an engager adapted to rotate said head; and a member having sliding engagement with said engager for rotating said engager as 85 said head and said engager reciprocate with relation to said member.

2. A device, as in claim 1, in which said member consists of a sleeve which fits over 90 said engager and has helical slots formed therein, in combination with projections upon said engager resting in said helical slots.

3. A device, as in claim 1, in combination with means for limiting the movement 95 of said member, so that said head and said engager will move relatively thereto.

4. In a device of the class described, the combination of: a polish rod; a head upon 100 said polish rod; a yoke upon said polish rod adapted to lift said head; an engager adapted to rotate said head; a member having sliding engagement with said engager for rotating said engager as said head and 105 said engager reciprocate with relation to said member, said member comprising a sleeve which fits over said engager and has inclined slots formed therein; projections on said engager resting in said slots; and means for limiting the movement of said 110 sleeve so that said head and said engager will move relatively thereto.

5. In a device of the class described, the combination of: a polish rod; a head upon 115 said polish rod; a yoke upon said polish rod adapted to lift said head; an engager adapted to rotate said head; a member having sliding engagement with said engager for rotating said engager as said head and 120 said engager reciprocate with relation to said member, said member comprising a sleeve which fits over said engager and has inclined slots formed therein; projections on said engager resting in said slots; and means for limiting the movement of said 125 sleeve so that said head and said engager will move relatively thereto; said limiting means comprising members extending from said sleeve, a stationary member adapted to be slidably engaged by said extending mem- 130

bers and adjustable stops upon said extending members.

6. In a device of the class described, the combination of: a polish rod; a head upon said polish rod; a yoke upon said polish rod; a yoke upon said polish rod adapted to lift said head, an engager adapted to rotate said head; a member having sliding engagement with said engager for rotating said engager as said head and said engager reciprocate with relation to said member, said member comprising a sleeve which fits over said engager and has inclined slots formed therein; projections on said engager resting in said slots; and means for limiting the movement of said sleeve so that said head and said engager will move relatively thereto, said head having ratchet teeth formed thereupon, said engager comprising pawls which engage said ratchet teeth.

7. In a device of the class described, the combination of: a polish rod; a head upon said polish rod; a yoke upon said polish rod adapted to lift said head; an engager adapted to rotate said head; a member having sliding engagement with said engager for rotating said engager as said head and said engager reciprocate with relation to said member, said member comprising a sleeve which fits over said engager and has inclined slots formed therein; projections on said engager resting in said slots; and means for limiting the movement of said sleeve so that said head and said engager will move relatively thereto, said limiting means comprising members extending from said sleeve, a stationary member adapted to be slidably engaged by said extending members and adjustable stops upon said extending members, said head having ratchet teeth formed thereupon, said engager comprising a ring mounted upon said head and yieldable pawls for engaging said ratchet teeth.

8. In a device of the class described, the combination of: a polish rod; a head upon said polish rod; a yoke upon said polish rod adapted to lift said head; an engager adapted to rotate said head; a member having sliding engagement with said engager for rotating said engager as said head and said engager reciprocate with relation to said member, said member comprising a sleeve which fits over said engager and has inclined slots formed therein; projections on said engager resting in said slots; and means for limiting the movement of said sleeve so that said head and said engager will move relatively thereto, said limiting means comprising members extending from said sleeve, a stationary member adapted to be slidably engaged by said extending members and adjustable stops upon said extending members, said head having ratchet teeth formed thereupon, said engager comprising a ring mounted upon said head and yieldable

pawls for engaging said ratchet teeth, said pawls being disposed in said projections.

9. In a device of the class described, the combination of: a polished rod; a head upon said polished rod; means for reciprocating said polished rod; an engager adapted to rotate said head; and a member having sliding engagement with said engager for rotating said engager as said head and said engager reciprocate with relation to said member.

10. In a pump, the combination of: a polished rod; a head secured to said polished rod; a yoke so placed as to support said head; a walking beam; said yoke being dependingly supported from the walking beam; an engaging member; means by which said engaging member turns said head in a positive direction and turns freely without engaging said head in a negative direction; well tubing; a member fixed with relation to the tubing of the well in which the polished rod is reciprocated by the walking beam; and means by which said fixed member turns said engaging member.

11. In a device of the class described, the combination of: a polished rod; a head secured to said polished rod; a yoke so placed as to support said head; a walking beam; said yoke being supported from the walking beam; an engaging member; means by which said engaging member turns said head in a positive direction and turns freely without engaging said head in a negative direction; a sleeve surrounding said engaging member and having inclined slots engaging projections on said engaging member; means for preventing said sleeve from turning with said head; and means for preventing said sleeve from reciprocating with said head during a portion of the pump stroke.

12. In a device of the class described, the combination of: a polished rod; a head secured to said polished rod; a yoke so placed as to support said head; a walking beam; said yoke being supported from the walking beam; an engaging member; means by which said engaging member turns said head in a positive direction and turns freely without engaging said head in a negative direction; a sleeve surrounding said engaging member and having inclined slots engaging projections on said engaging member; means for preventing said sleeve from turning with said head; and means, secured to the well tubing in which the polished rod is reciprocated, for preventing said sleeve from reciprocating with said head during a portion of the pump stroke.

In testimony whereof, I have hereunto set my hand at Los Angeles, California, this 26th day of October, 1922.

DELBERT F. AXELSON.

CERTIFICATE OF CORRECTION.

Patent No. 1,635,776.

Granted July 12, 1927, to

DELBERT F. AXELSON.

It is hereby certified that error appears in the printed specification of the above numbered patent requiring correction as follows: Page 3, line 6, claim 6, strike out the words "a yoke upon said polish rod"; same page, line 121, claim 12, after the word "head;" insert the words and semi-colon "well tubing;"; and that the said Letters Patent should be read with these corrections therein that the same may conform to the record of the case in the Patent Office.

Signed and sealed this 16th day of August, A. D. 1927.

Seal.

**M. J. Moore,
Acting Commissioner of Patents.**
